ROTARY PERCUSSION DRILL

Ernest Craig, Lakefield, Ontario, Canada

Application November 17, 1950, Serial No. 196,318

6 Claims. (Cl. 125—33)

1

This invention relates to improvements in percussion rock drills of the type in which a rapidly rotating hammer is utilized to strike the drill shank or a tappet interposed between the drill shank and hammer to thereby effect rapid vibratory reciprocation of the drill shank in the direction of its length.

The principal object of the invention is to provide an improved striking action and in particular to provide the desired hammer blow accurately timed and directed effectively through to the steel and permitting the hammer to lift upon striking while eliminating destructive hammer back lash and consequent wearing and chattering, providing substantially vibrationless long-life operation.

Another important object is to provide a rugged efficient drill as aforesaid being capable of effective drilling when operated by a relatively low horsepower drive, enabling the invention to be embodied in a compact relatively lightweight portable drill.

The principal feature of the invention consists in employing a valving action to control a hammer mounted in a revolving carrier bodily translated about a central axis to lock the hammer against movement under centrifugal force while remote from the impact position and to free the hammer at impact to deliver its blow through to the steel under the full centrifugal force and to thereafter freely lift from the steel.

Another feature consists in providing a timing mechanism to time the blow and ensure operation of the valve to free the hammer at impact.

The above objects and features will be readily understood from the following description taken in reference to the accompanying drawings in which Figure 1 is a vertical sectional view on the line 1—1 of Figure 2 through a percussion drill constructed in accordance with this invention.

Figure 2 is a vertical sectional view taken through the drill at right angles to Figure 1 on the line 2—2 of Figure 1.

Figure 3 is a vertical section taken through the cage and hammer illustrating the position of the hammer at impact.

Figure 4 is a view similar to Figure 3 but showing a different position of the hammer with the cage rotated.

Figure 5 is a view similar to Figure 3 showing still a different position of the hammer and cage rotation.

The drill herein disclosed is generally similar to my co-pending application Serial Number 165,635 employing a hammer mounted in a ro-

2

tatable carrier revolved about the rotary axis of the drill by a timing mechanism which correctly times the blow with the hammer moving with substantially linear motion in the direction of the tappet, as explained in said application.

With reference to the drawings, the drill casing 1 is shown as a circular casting formed with internal flanges 2 and an axially offset extension 3 having a central bore or passage 4 in which is slidably received a tappet or steel shank 5 to project within the casing.

Secured to the casing 1 are the closing face plates 6 and 7 held outwardly from the flanges 2 by their circular flanges 8 and bolted to the casing by bolts 9. Each of the face plates 6 is formed with a central journal boss 10 in which is mounted a journal 11 held in position by a plate 12. Journalled in each of the journals 11 is a rotor member 13 having a hub 14 received within the inner face 15 of its respective adjacent face plate abutting the adjacent journal 11 and having a shaft extension 16 received within the journal.

The hubs 14 of the rotor members 13 have secured thereto radial flanges 17 formed to receive journals 18 held in position by the plates 20.

Extending from one of the shaft extensions 16 is a rotor drive shaft 21.

The journals 18 of the opposing rotor members 13 are axially aligned and journalled therebetween are cages 22 formed with axially aligned stud shafts 23 received within the journals.

Mounted within the flange 8 of one of the face plates 6 is an internally toothed ring gear 24, and the cages 22 are formed at one end with teeth 25 forming a spur gear which meshes with and is substantially one-half the diameter of the ring gear 24 as the rotor 13 is rotated.

The ring gear 24 and the gears 25 form the timing mechanism to time the blow delivered to the steel 5, as hereinafter more fully explained.

Each of the cages 22 is provided with an arcuate recess or slot 26 extending through the cage, and mounted in this recess 26 is a hammer 27 free to slide to the position of Figures 1 and 3 where further outward movement is limited by the stop 28 formed in the cage engaging stop 29 of the hammer. The hammer is formed with a striking face 30 directing the hammer blow through to the steel 5.

Mounted in a recess or slot 31 intersecting the recess 26 is a valve or locking member 32 having an arcuate hub portion 33 fitting a circular portion 34 of the slot 31 to support the valve for pivotal movement into and out of contact with

the hammer 27. The valve or locking member is formed with stepped stop surfaces 35 and 36 to engage the back stop 37 formed on the hammer, stop 35 engaging the back stop with the valve swung against the hammer, and stop 36 engaging the back stop 37 to limit lifting of the hammer following impact.

The hammer and valve 27 and 32 may be inserted from the end of the cage opposite to the teeth 25 and the end plates 38 fastened in position by threading onto the threaded ring segments 38' of the cage.

In operation the drill is driven from a small motor operating the shaft 21 which in turn drives the rotor 13 carrying the cages 22. The cages are thus revolved about the axis of the casing and as these cages are revolved their gears 25 engage the ring gear 24 effecting rotation of the cages which serve as the carrier members for the hammers 27.

The cages 22 are of a size that their gears 25 are substantially one-half the diameter of the ring gear 24 and an exact timing is afforded by these gears to bring the cages 22 to the position of Figures 1 and 3 each revolution of the rotor with the cages rotating in the direction of the arrow.

It will be seen particularly from Figure 1 that the position of the hammer 27 is such that under the centrifugal force developed upon rotation of the rotor it is being urged outwardly of the axis of the rotor and casing to its striking position against cage stop 28 to effect a blow directed longitudinally of the steel 5 which blow is delivered with substantially linear motion in the said longitudinal direction of the steel due to the relation of the cage gear being one-half the diameter of the ring gear 24 as explained in the aforesaid application Serial No. 165,635.

Thus as the rotor is driven and the cages rotate the hammers 27 will impart a succession of effective hammer blows correctly timed and directed through timing of the cage to drive the steel longitudinally.

Figures 3 to 5 clearly illustrate the function of the valve or locking member during rotation of the cage to prevent destructive back lash of the hammer. In the position of Figure 3, that is, at impact with the steel 5, the valve 32 is swung to a position so that its stop 35 is clear of the hammer stop 37. Thus at impact the hammer is free to lift following the impact blow sliding upwardly in its recess 26 so that there will be no vibration imparted to the cage and rotor.

Following impact and rotation of the rotor and cage to clear the steel 5 there will still be a centrifugal force acting outwardly of the axis of the rotor to force the hammer against the cage stop 28, this centrifugal force gradually diminishing as the cage is rotated to the position of Figure 4 wherein the centrifugal force will be acting to urge the hammer against the wall of its recess 26.

At this position it will be seen that the valve 32 will have dropped into engagement with the hammer 27 under its own weight, pivoting about its hub portion 33, bringing the hammer stop 37 and valve stop 35 into engagement, blocking movement from the hammer away from the cage stop 28.

The valve 32 remains in contact with the hammer through the position illustrated in Figure 5 wherein the centrifugal force acting on the hammer is urging the hammer away from the cage stop 28.

cage stop 28. Without the provision of the valve 32 the hammer thus would be driven against its back stop every time it is rotated through 180° while being translated about the axis of the casing 1 by the rotor 13.

The pressure exerted by the hammer 27 under the action of centrifugal force against the stop 35 of the valve binds the valve in its hammer-locking position of Figure 3 and the valve is held in place from the position of Figure 3 by this binding action until the cage has been rotated through another 90° to again bring the hammer extending substantially transversely of the radial of said rotor 13, following which the valve is free to drop out under its own weight as the cage further rotates to the position of Figures 1 and 3, freeing the hammer for its timed impact with the steel 5.

The valving action disclosed is extremely simple and functions automatically under centrifugal force and the result of its use is to not only free the drill from vibration under back lash occurring where no valve is present but further, very materially increases the life of the cage and hammer elements in eliminating the back lash chatter.

In the disclosure specific simplified valve structure is shown but it will be understood that various forms of valves may be utilized without departing from the scope of the appended claims.

It will also be understood that the particular form and details of the casing and hammer may be varied within the spirit of the invention.

What I claim as my invention is:

1. In a rotary percussion drill, a rotor, a rotating cage eccentrically mounted on said rotor, a hammer slidably mounted in said cage, a steel adapted to be projected into the path of said hammer under revolution of said cage and rotor to permit said hammer to strike said steel, and centrifugally operated means locking said hammer against movement in said cage immediately subsequent striking said steel and freeing said hammer during impact with said steel to lift following striking of said steel.

2. In a rotary percussion drill, a rotor revolving about a central axis, means for driving said rotor, a cage rotatably mounted on said rotor to revolve about an axis displaced from said central axis, means effecting rotation of said cage in a direction opposite to and at a greater speed than said rotor, a hammer slidably mounted in said cage for limited movement relative thereto to permit hammer action, a steel adapted to be projected into the path of said hammer traced upon revolution of said cage and rotor as said hammer is urged under centrifugal force to a limit position in said cage to strike said steel, translation of said cage under rotor rotation carrying said cage away from said steel in direction opposite to direction of hammer blow, and a centrifugally operated locking member mounted in said cage and movable in the plane of and on a path intersecting with said hammer to lock said hammer against displacement from said limit position following striking of said steel and to free said hammer at impact with said steel to permit said hammer to rebound.

3. In a rotary percussion drill, a casing, a tappet member reciprocally arranged to project within said casing, an internally toothed ring gear mounted within said casing, a rotor revolvably mounted to rotate on the axis of said ring gear, at least one cage carried by said rotor hav-

ing a gear substantially one-half the diameter of said ring gear meshing with the teeth of said ring gear to rotate said cage in opposite direction to and at twice the speed of said rotor, a hammer carried by said cage and mounted for movement relative said cage to permit hammer action, the relation of said ring and cage gears being timed such as to urge said hammer to a limit position in said cage to strike said tappet with substantially linear motion directed longitudinally of the tappet, and a centrifugally operated locking member mounted in said cage and movable in the plane of and on a path intersecting with said hammer to lock said hammer against displacement from said limit position following striking of said steel and to free said hammer at impact with said steel to permit said hammer to rebound.

4. In a rotary percussion drill, a rotor revolving about a central axis, a cage rotatably mounted on said rotor to revolve about an axis displaced from said rotor axis, a steel slidably supported in said casing to project therewithin, a hammer mounted in a slot in said cage for movement relative said cage, timing means driving said cage upon rotation of said rotor to locate said hammer upon rotor and cage rotation to strike said steel while urged under centrifugal force in the direction of said steel, a locking member pivoted on said rotor to swing about an axis parallel said rotor axis under centrifugal force under rotor rotation in an arc co-planar with and intersecting the path of movement of said hammer, said locking member being located with respect to said hammer and with reference to said rotor axis to lie outwardly of and urged away from said hammer preceding impact and to lie inwardly of and urged into contact with said hammer following impact, said hammer and locking member being formed with co-operating surfaces to lock said hammer against movement relative said cage with said locking member urged into engagement with said hammer.

5. In a percussion drill, a casing, an internally toothed ring gear mounted within said casing, a rotor mounted to rotate on the axis of said ring gear, at least one cage of substantially one-half of the diameter of said ring gear eccentrically and rotatably mounted on said rotor and provided with a gear of a diameter equal to cage diameter and meshing with said ring gear, means for revolving said rotor to drive said cage through said ring gear at twice rotor speed, a hammer carried by said cage and having a striking face moving in a substantially linear path under rotor and cage rotation, a tappet reciprocally arranged to project within said casing, the timing of said ring and cage gears being arranged to bring said ham-

mer face against said tappet while moving with substantially linear motion in direction of said tappet, said hammer being mounted for movement relative said cage upon striking said tappet, and a locking member locking said hammer against movement following impact with said tappet and freeing said hammer at impact to rebound.

6. In a percussion drill, a casing, an internally toothed ring gear mounted within said casing, a rotor mounted to rotate on the axis of said ring gear, at least one cage of substantially one-half the diameter of said ring gear eccentrically and rotatably mounted on said rotor and provided with a gear of a diameter equal to cage diameter meshing with said ring gear, means for revolving said rotor to drive said cage through said ring gear at twice rotor speed, said cage having a slot therein opening to the periphery thereof, a hammer mounted in said slot for relative movement relative said cage, a tappet reciprocally arranged to project within said casing, the timing of said ring and cage gears being arranged to bring said hammer against said tappet while moving in a direction substantially aligned with the longitudinal direction of said tappet, and a centrifugally operated locking member mounted in said cage to swing about an axis parallel said rotor axis under centrifugal force under rotor rotation in an arc co-planar with and intersecting the path of movement of said hammer, said locking member being located with respect to said hammer and with reference to said rotor axis to lie outwardly of and urged away from said hammer preceding impact and to lie inwardly of and urged into contact with said hammer following impact, said hammer and locking member being formed with co-operating surfaces to lock said hammer against movement relative said cage with said locking member urged into engagement with said hammer.
